EARRING FINDING

William Anthony Carroll, Warwick, R.I., assignor to The Lorac Company, Inc., a corporation of Rhode Island

Filed Apr. 17, 1963, Ser. No. 74,482

Term of patent 7 years

(Cl. D45—9)

FIG. 1

FIG. 2

FIG. 4

FIG. 1 is a perspective view of the earring finding showing my new design;

FIG. 2 is a side elevational view thereof on a slightly reduced scale;

FIG. 3 is a fragmentary end view thereof with one of the jaws broken away for convenience of illustration; and

FIG. 4 is a view looking at the other end of the earring finding.

I claim:

The ornamental design for an earring finding, substantially as shown.
